UNITED STATES PATENT OFFICE

149,742

DESIGN FOR A BOX

Marguerite Casseus D'Hennery, Paris, France

Application June 20, 1946, Serial No. 130,888

Term of patent 3½ years

(Cl. D58—12.6)

To all whom it may concern:

Be it known that I, Marguerite Casseus D'Hennery, a citizen of France, residing at 185 Boulevard Murat, Paris, France, have invented a new, original, and ornamental Design for a Box, of which the following is a specification, reference being had to the accompanying drawing, forming part thereof.

In the drawing:

Fig. 1 is a perspective view of a box, in closed position, showing my new design;

Fig. 2 is a view similar to Fig. 1, but showing the box in open set-up position;

Fig. 3 is a sectional view on the line 3—3 of Fig. 1; and

Fig. 4 is a sectional view on the line 4—4 of Fig. 2.

I claim:

The ornamental design for a box, substantially as shown.

MARGUERITE CASSEUS D'HENNERY.
